Primary Examiner — Holly H Baynham(74) *Attorney, Agent, or Firm* — Dykema Gossett PLLC(57) **CLAIM**

The ornamental design for a waterproof purse cover, as shown and described.

DESCRIPTION

FIG. 1 is an isometric view of a waterproof purse cover according to the present invention.

FIG. 2 is a front elevational view of the waterproof purse cover depicted in FIG. 1.

FIG. 3 is a top plan view of the waterproof purse cover depicted in FIG. 1.

FIG. 4 is a back elevational view of the waterproof purse cover depicted in FIG. 1.

FIG. 5 is a bottom plan view of waterproof purse cover depicted in FIG. 1.

FIG. 6 is a left side elevational view of waterproof purse cover depicted in FIG. 1; and,

FIG. 7 is a right side elevational view of waterproof purse cover depicted in FIG. 1.

The broken lines visible on the surface of the Waterproof Purse Cover represent claimed stitching.
